UNITED STATES PATENT OFFICE.

MIRABEAU SIMS, OF PHILADELPHIA, PENNSYLVANIA.

TRANSLATING MATERIAL.

Application filed February 11, 1920. Serial No. 357,949.

To all whom it may concern:

Be it known that I, MIRABEAU SIMS, a citizen of the United States, residing at Philadelphia, county of Philadelphia, State 5 of Pennsylvania, have invented a new and useful Means for Translating Material, of which the following is a specification.

My invention relates to improvements in means for the pneumatic translation of material, and is especially adapted for taking material from the hold of a barge. The invention especially comprises means for moving the expansion tank to a required elevation in connection with the barge during 10 the process of translation and for maintaining the same in such position, and also means for lowering said expansion tank to a position near the deck of the barge when the apparatus is not in operation for the 15 translation of material.

The invention also comprises various improvements in details of construction.

Referring to the drawings, which illustrate, merely by way of example, suitable 25 means for the embodiment of my invention—

Fig. 1 is a plan view of a barge equipped with apparatus containing my improvements.

Fig. 2 is a side elevation of same.

Fig. 3 is a cross-sectional elevation on line 3—3 of Fig. 2.

Fig. 4 is an enlarged sectional detail of part of the structure shown in Fig. 3.

Fig. 4^a is a detail in plan showing a portion of the material conveying system.

Fig. 5 is a plan view of the top of the tower and the expansion tank on an enlarged scale.

Fig. 6 is a side elevation of the upper portion of the tower with the expansion tank in operative position.

Fig. 7 is an elevation of the lower portion of the tower with the expansion tank 45 in the lower position when not in operation.

Fig. 8 is a detail in side elevation of means for guiding the tank in its movement.

Fig. 9 is a cross-section on lines 9—9 of Fig. 8.

Fig. 10 is a fragmentary view showing means for securing the tank in position.

Fig. 11 is a section on line 11—11 of Fig. 10.

Fig. 12 is a horizontal section on line 55 12—12 of Fig. 2 on an enlarged scale.

Fig. 13 is a detail in elevation of the tank and its supporting means.

Fig. 14 is a sectional view on an enlarged scale of the dash-pot for the counter balancing weights.

66

Similar numerals refer to similar parts throughout the several views.

Referring especially to Figs. 1 and 2, 15 indicates the barge containing material which is to be translated therefrom by 65 means of my improved pneumatic apparatus. Upon this barge is permanently secured the open or skeleton tower 16. This tower 16 is provided with the four T-irons 17 extending from the top to the bottom of 70 the same forming tracks or guides for the rollers 18, connected to the expansion tank 19 for guiding said tank in its movement upwardly and downwardly. To lugs or other suitable devices 20 connected to tank 75

19 are secured the four cables 21 passing over the pulleys 22. To the lower ends of these cables 21 are secured the weights 23 which tend to counterbalance the expansion tank 19 and normally serve to pull the tank 80 to the elevated position, at the top of the tower as shown in Figs. 2, 3 and 6. These weights 23 are guided by the T-irons 24, also connected with the tower 16. The dash-pots 25 are provided at the bottom of 85 the tower as means for cushioning the downward movement of the weights, especially in case of the break of the cable or other accident.

Secured to the lower part of the expansion tank 19 are the chains 26. These chains are shown as coming to a point beneath the tank, approximately in line with the axis thereof. Connected to these chains,

at said point, is the cable or chain 27 which 90 runs over pulleys 28 and 29 to the drum 30, connected by clutch 31 to the engine 32, so

that by rotating the drum 30 the cable or chain 27 is wound upon the drum and the expansion tank 19 is pulled down to a position 95 close to the deck of the barge as shown in Fig. 7, ensuring at all times, physical control of the expansion tank. By reversing the movement of the drum 30, the cable or chain 27 is unwound thereby permitting 100 the weights 23 to pull the tank 19 to the elevated position, that is to the top of the tower as shown in Figs. 2, 3 and 6.

When the tank 19 is in the elevated position as shown in Figs. 2 and 6, it is con- 105

55 110

When the tank 19 is in the elevated position as shown in Figs. 2 and 6, it is con- 110

2
nected at the top thereof to the exhaust pipe 33, which in turn is permanently connected at its lower end with the rotor or exhauster 34 driven by engine 32 through clutch 35. At a lower point in the tank is provided the pipe or nozzle 36 to which is connected the material pipe 37. This material pipe 37 extends downwardly and has a horizontal extension 38 adapted to lie along the bottom of the barge near the middle part thereof. This extension 38 is provided with a number of cross formations 39, having gates 40; and adjacent thereto are provided the hoods 41. The gates 40 are connected to rods 42 which are threaded at their upper ends as at 43 and provided with hand wheels 44 to manipulate the same to open and close said gates.

The connection between the exhaust pipe 33 and the top of tank 19, as at 33^a, is a disengageable connection provided with suitable means for readily making a pneumatic or airtight joint. The details of this joint however form no part of the present invention. The connection between the material pipe 37 and tank 19, or the nozzle 36, secured within said tank is also a disengageable connection having similar means for convenient engagement and disengagement and for securing an efficient airtight joint.

When the tank is raised to the elevated position as shown in Figs. 2 and 6, it is secured against accidental displacement by means of the bolt or bolts 45, one being shown in detail in Figs. 10 and 11. This bolt is connected in the sleeve 46 of the tower structure and is adapted to engage in the socket 47, provided in the lug 48, connected with the tank 19. This bolt is held in locking position by means of the pin 49.

Beneath the tank 19, and connected therewith, is provided the air-locking discharge mechanism 50, having a discharge nozzle 51, adapted to have disengageable connection with the discharge pipe 52 which delivers to any desired point. This air-locking discharge device 50 forms no part of the present invention.

50 As a security to prevent accidental falling of the weights due to breaking of cables or other cause, the pins 53, as shown in Fig. 2, are provided passing through the portions of the tower structure just beneath the weights when the same are in the elevated position.

In operation it will be understood that the exhaust pipe 33 and the material pipe 37 are permanently secured to and supported by the tower 16, while the extension 38 of pipe 37 lies along the middle part and near the bottom of the barge 15.

The especial advantage of lowering the expansion tank 19 to the deck of the barge is that we thereby diminish the resistance

to the wind, since very little resistance to the wind is presented by the skeleton tower and the pipes connected therewith, so that the barge with or without its load may make the voyage desired without danger incident to high winds.

When it is desired to unload the barge the expansion tank 19 is moved to the elevated position as shown in Fig. 6, for example, by unwinding the drum 30 and permitting the weights 23 to pull the tank to the top of the tower, where it is secured by the means hereinbefore described.

The air-tight connections are then made between the upper ends of pipes 33 and 37, and the tank, and by operating the clutch 35 the rotor is actuated to cause the necessary minus pressure in tank 19.

The various valves 40 are then operated as required to permit the material contained in the barge to flow into the pipe 38 and float upwardly through pipe 37 to the expansion tank 19. The material is separated from the air currents in tank 19 and falls to the bottom thereof. From the bottom of tank 19 the material passes through the air-locking discharge device 50 and pipes 51 and 52 to the desired point of delivery.

The hoods 41 which are provided over the intake openings of the crosses connected with pipe extension 38, serve to prevent the material from clogging the openings, so that the desired flow may be secured through these openings into pipe 38.

The valves 40 are opened in such order or sequence as may be desired to secure a uniform or even translation of the material from the hold of the barge.

When the translation of the material from the barge is completed, the clutch 35 is operated to disengage the rotor from the engine, and the pipes 33, 37 and 52 are disconnected, at their upper ends, from tank 19. The clutch 31 is then operated to connect the drum 30 with the engine 32, to wind up the cable or chain 27 to pull the tank down to the position close to the deck, as indicated in Fig. 7.

It will of course be understood that the securing pins 45, are first withdrawn to permit the descent of the tank. Also after the weights 23 have been moved to the elevated position, as shown in Fig. 2, caused by the descent of the tank 19, said weights are secured in position by the pins 53.

The barge is then ready for another voyage with the tank in position to present the least resistance to the wind.

What I claim is:

1. In a pneumatic translating device for barges or other floating vessels, the combination of an expansion tank, means including an exhaust pipe adapted to be connected with said tank for producing a pressure less than atmospheric therein, a material pipe

leading from the hold of the vessel and adapted to be connected with said tank, means connected with the vessel for supporting the tank, and means for arbitrarily moving the tank to the required elevation for connection with said pipes for translating the material and for lowering the tank when the translating device is not operating.

2. In a pneumatic translating device for barges or other floating vessels, the combination of an expansion tank, means including an exhaust pipe adapted to be connected with said tank for producing a pressure less than atmospheric therein, a material pipe leading from the hold of the vessel and adapted to be connected with said tank, said material pipe having an extension adapted to lie near the bottom of said hold and parallel with the keel thereof, means connected with the vessel for supporting the tank and means for arbitrarily moving the tank to the required elevation for connection with said pipes for translating the material and for lowering the tank when the translating device is not operating.

3. In a pneumatic translating device for barges or other floating vessels, the combination of an extension tank, means including an exhaust pipe for producing a pressure less than atmospheric therein, a material pipe adapted to be connected therewith and leading from the hold of the vessel, said material pipe having an extension adapted to lie near the bottom of said hold and extending approximately throughout its length, means connected with the vessel for supporting the tank and means for arbitrarily moving the tank to the required elevation for translating the material and for lowering the tank when the translating device is not operating.

4. In a pneumatic translating device for barges or other floating vessels, the combination of an expansion tank, means including an exhaust pipe adapted to be connected with said tank for producing a pressure less than atmospheric therein, a material pipe leading from the hold of the vessel and adapted to be connected with said tank, said material pipe having an extension in said hold approximately throughout its length, and provided with a plurality of valve controlled intake openings spaced apart, means connected with the vessel for supporting the tank and means for arbitrarily moving the tank to the required elevation for translating the material and for lowering the tank when the translating device is not operating.

5. In a pneumatic translating device for barges or other floating vessels, the combination of an expansion tank, means including an exhaust pipe adapted to be connected with said tank for producing a pressure less than atmospheric therein, a material pipe

leading from the hold of the vessel and adapted to be connected with said tank, said material pipe having an extension in said hold approximately throughout its length, and provided with a plurality of separated valve controlled intake openings and having hoods positioned over said intake openings, means connected with the vessel for supporting the tank and means for arbitrarily moving the tank to the required elevation for translating the material and for lowering the tank when the translating device is not operating.

6. In a pneumatic translating device for barges or other floating vessels, the combination of an expansion tank, means including an exhaust pipe adapted to be connected with said tank for producing a pressure less than atmospheric therein, a material pipe leading from the hold of the vessel and adapted to be connected with said tank, means connected with the vessel for supporting the tank comprising a skeleton tower connected to the vessel and extending upwardly above the deck thereof, and means for arbitrarily moving the tank to the required elevation for translating the material and for lowering the tank when the translating device is not operating.

7. In a pneumatic translating device for barges or other floating vessels, the combination of an expansion tank, means including an exhaust pipe adapted to be connected with said tank for producing a pressure less than atmospheric therein, a material pipe leading from the hold of the vessel and adapted to be connected with said tank, means connected with the vessel for supporting the tank, means for arbitrarily moving the tank to the required elevation for translating the material and for lowering the tank when the translating device is not operating, and means for disengageably connecting the exhaust pipe and the material pipe with the tank so as to form airtight joints therewith.

8. In a pneumatic translating device for barges or other floating vessels, the combination of an expansion tank, means including an air-exhausting rotor and an exhaust pipe for producing a pressure less than atmospheric within the tank, a material pipe adapted to be connected with the tank, and leading from the hold of the vessel, means for supporting the tank and means for arbitrarily moving the tank to the required elevation for translating the material and for lowering the tank when the translating device is not operating.

9. In a pneumatic translating device for barges or other floating vessels, the combination of an expansion tank, means for producing a pressure less than atmospheric therein, a material pipe leading from the hold of the vessel and adapted to be con-

nected with said tank, means connected with the vessel for supporting the tank and means, including a winding drum, counter-balancing weights and suitable connecting devices, for arbitrarily moving the tank to the required elevation for translating the material and for lowering the tank when the translating device is not operating.

10. In a pneumatic translating device for barges or other floating vessels, the combination of an expansion tank, means including an exhaust pipe adapted to be connected with said tank for producing a pressure less than atmospheric therein, a material pipe leading from the hold of the vessel and adapted to be connected with said tank, means connected with the vessel for supporting the tank in elevated position, means, including a winding drum, counter-balancing weights and suitable connecting devices, for arbitrarily moving the tank to the required elevation for translating the material and for lowering the tank when the translating device is not operating, and means for cushioning the downward movement of the weights.

11. In a pneumatic translating device for barges or other floating vessels, the combination of an expansion tank, means including an exhaust pipe adapted to be connected with said tank for producing a pressure less than atmospheric therein, a material

pipe leading from the hold of the vessel and adapted to be connected with said tank, means, including a skeleton tower connected with the vessel for supporting the tank, means, including a winding drum, counter-balancing weights and suitable connecting devices, for arbitrarily moving the tank to the required elevation for translating the material and for lowering the tank when the translating device is not operating, and means for locking the tank against accidental displacement.

12. In a pneumatic translating device for barges or other floating vessels, the combination of an expansion tank, means, including an exhaust pipe adapted to be connected with said tank, for producing a pressure less than atmospheric therein, a material pipe leading from the hold of the vessel and adapted to be connected with said tank, means, including a skeleton tower connected with the vessel for supporting the tank, means, including a winding drum, counterbalancing weights and suitable connecting devices, for arbitrarily moving the tank to the required elevation for translating the material and for lowering the tank when the translating device is not operating, and means for locking the weights against accidental downward movement.

MIRABEAU SIMS.
